By B. C. Converse, Atty.

UNITED STATES PATENT OFFICE.

TIMOTHY ROGERS, OF SPRINGFIELD, OHIO, ASSIGNOR TO THE ROGERS FENCE COMPANY, OF SAME PLACE.

IRON FENCE.

SPECIFICATION forming part of Letters Patent No. 293,674, dated February 19, 1884.

Application filed March 24, 1883. (No model.)

To all whom it may concern:

Be it known that I, TIMOTHY ROGERS, a citizen of the United States, residing at Springfield, in the county of Clarke and State of Ohio, have invented certain new and useful Improvements in Iron Fences; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in iron fences.

My invention relates to improvements in that class of iron fences having punched rails.

My invention relates, further, to the manner of fastening the picket-rod, its ornament, and the rail together.

My invention relates, further, to a peculiar construction of the ornament, by which it is better adapted to be secured to the picket to strengthen the ornament-connections with both picket and rail, and at the same time to allow of the adjustment of the fence, if required.

My invention relates, further, to the rail-connections and the means by which they are strengthened.

My invention relates, further, to the construction of the line-post and its several connections as applied in the fence.

Figure 1 is a front elevation of a picket, a portion of rail in which it is inserted, and one of the rail and brace connections between the pickets of the line-post, the pickets not being shown. Fig. 2 is a section through line *y*, Fig. 1. Fig. 3 is a cross-section through line *x*, Fig. 2, enlarged. Fig. 4 is a side elevation of a portion of the picket-rod with its engaging-notch. Fig. 5 is a cross-section of the same through line *z*, Fig. 4. Fig. 6 is a rear view of that portion of the ornament which embraces the rail and picket. Fig. 7 is a cross-section through line *y*, enlarged. Fig. 8 is an inside view of the rail-connection seen in Figs. 1 and 7, looking from rear to front. Fig. 9 is a front view of the foot of the

line-post, with parts of two pickets inserted 50 therein, a part being broken away to show the small hole at the bottom of the picket to let the water escape. A vertical section through the socket for the picket-rod is also shown in detail. Fig. 10 is a side view of the upper 55 part of the line-post base, with the part seen in Fig. 9 attached. Fig. 11 is a top view of the same. Fig. 12 is a view, from the under side, of a piece of rail with a cross-section of the picket inserted and fastened in place with- 60 out the ornament.

In this fence I use a T-channel rail, by preference, although other forms of rail may be used with this kind of picket.

The construction of the picket-rod and the 65 means by which it is engaged with the rail are first in order. The iron rod is rolled with an angle upon one side, showing in its cross-section a cylinder with an angle upon one side ex- 70 tended beyond the circle of the same, as seen in the two cross-sections, Figs. 3 and 5. To adapt the rail and picket-rod for engagement with each other, the rail has a hole of the same shape with the picket punched in it. This hole is made with the angle in the central longitudinal line of the rail, in order to allow the picket-rod to be inserted and rotated on its 75 axis until the angle is brought to the inner surface of the flange of the rail, which allows the notch *e* to engage the edge of the rail in 80 the circular part of the hole *d*, (see Fig. 12,) and brings the angle *d* in the position to allow of the fastening of the rod, which will be 85 hereinafter described. At the point where the angle of the picket-rod is cut away to form the notch *e* the rod is left cylindrical in its cross-section, as shown in Figs. 4 and 5, to allow of its being easily turned in the hole *d*, to 90 bring its angle transversely to the line of the rail and in contact with the inner surface of the flange on its edge.

The picket-rod in this fence can be secured to the rails, either with or without the ornament. When used with an ornament, the latter is made to engage both the rail and the 95 picket-rod. The ornament used is one with a loop at its upper and lower ends, through which the picket-rod extends. That part of

the frame which encircles the picket-rod is made to conform to its surface, those loops upon the front side having a rear inner angle, into which the angular part of the picket-rod 5 enters. The two loops c' , which connect the main circular frame-bars of the ornament, are bent backward over the front flange of the rail, and have upon their rear sides two sprockets, c'' , which straddle the angle d' on the front 10 of the picket-rod. These are driven back by a set-punch, bending the bar c' back from its normal position, as seen in Fig. 3. By this means the rod of the picket is prevented from turning out of place. The main frame of the 15 ornament extends over the front of the rail in the usual manner. By reference to the two Figs. 2 and 3, the position of the ornament and its fastenings to both picket and rail can be seen, and the construction of the parts de- 20 scribed be fully understood. Where the ends of the rails connect, and the line-post is usually set, there is an adjustable box-sleeve, B, incasing the rail ends and connecting them together. It is formed of two short pieces of 25 angle-iron, f , open at the ends, and engaged together at their edges, which have an angular groove, f'' , in one, on the inside, and an angle, e' , formed on the edge of the other, which enters it, as seen in the detail, Fig. 7. These 30 are held together by a bolt, t , which extends through the upper end of the brace h of the line-post C. An inside view of the front section f of the sleeve B is shown in Fig. 8, with the ends of the opposite rails, b , therein. 35 To retain the rails in position, and at the same time allow for expansion and contraction, the rail-flange has an open notch, g' , cut therein, with which a lug, g , cast on the inside of one of the angle-pieces f , engages on either side of 40 the fastening-bolt t . The notch has a space on either side of the lug, to allow for any endwise movement of the rails. The lower end of the brace h extends through an oblong hole, i , in the rear end of arm j of the post-base D, where 45 it is held in adjustment by a set-screw, i' , entering the end of the arm and engaging the brace. The oblong hole i allows of the proper adjustment of the brace h . The front of the base has an elongated vertical hole, p , therein, 50 to admit of a bolt, r , extending down through the vertical oblong slot p' of the foot-piece C' of the line-post, which crosses the base at right angles. The piece C' is in two halves, l and l' , divided vertically, and has a socket, k , at 55 either end for the insertion of the picket-rods a' therein. The hole k is slightly oblong, to allow of the inclination of the picket-rod in the direction of the fence-line. At the bottom of each hole k is a smaller hole, o' , made by 60 the inward extension of a flange, o , at the bottom, as seen in the detail view, Fig. 9. This flange allows the lower end of the picket-rod to rest thereon, and the small hole gives escape to any water that may collect in the 65 socket. The foot-piece sections and their picket-rods are secured together by a bolt, m ,

at either side of its center. The sockets are cylindrical in outer form, and extend high enough to secure the picket-rods firmly. The rod is adjustable therein in line of the fence, 70 as seen in dotted lines, Fig. 9, and also up or down within the socket.

When dispensing with ornaments and their connections, the pickets are turned on their axis, the same as before stated, with angle d' 75 on one side next to the inner surface of the rail-flange, which may be either to the front or rear side. A notched or forked punch is placed against the rail-flange, with its points on either side of the line of the angle, and by 80 a blow given to it the notches n are indented into the rail, so as to raise a projection on the inside of the flange on each side of the angle d' , thus securing the picket-rod firmly therein, as seen in the view of the under side of the 85 rail, Fig. 12. These indents may be made either above or below the notch e in the picket-rod, or on the upper or lower side of the rail, as preferred.

I wish to be distinctly understood as reserving the right to file a separate application for a patent for the iron rod used in the construction of the picket of this fence.

I claim as my invention—

1. In a punched-rail fence, the combination, 95 with a cylindrical picket-rod formed with an angle on one side and a notch in said angle, and adapted to be engaged with the rail, as de- 100 scribed, of an ornament having sprockets ex- 100 tending from its frame-bars upon either side of said picket-rod, which, when said frame- 105 bars are bent or set back against the rod, will straddle said angle and secure the rod from turning axially, substantially as set forth.

2. In a punched-rail fence, an ornament for 105 a picket-rod formed with an angle thereon, having sprockets extending across the line of 110 the rod, and adapted to engage therewith by being set back with a punch beyond the front line of the rail, substantially as set forth.

3. An adjustable sleeve-connection for the 115 rails of an iron fence, consisting of two short angular pieces of iron with engaging angles and grooves on their flanges, to retain them in position, and lugs cast on the inside of one of the sections, adapted to engage with notches in the end of the inserted rail, whereby the 120 connection is made and the adjustment secured, and having a fastening-bolt securing the end of the brace of the line-post, the two 120 sections of the sleeve, and the rails together, substantially as set forth.

4. The combination, with the T-channel 125 rails b , having notches g' , of the box-sleeve connection B, formed of the two angular sec- 130 tions f and f' , having lugs g , and each provided with the angles e' and the grooves f'' , to adapt them for engaging each other, the brace h of the line-post, and the bolt t , by which the whole is secured together, substantially as 130 specified.

5. A foot-piece for a line-post in two longi-

tudinal vertically-divided sections, having a central oblong hole to adapt it for adjustment upon the base, and having a socket in either end for the insertion of the picket-rod, said 5 sockets being made with a longitudinally oblong hole, to adapt them for the adjustment of the picket in the direction of the fence-line, and with a drainage-hole of less diameter at the lower end of the socket, substantially as set 10 forth.

6. In a line-post, the combination, with the base D, having the oblong slot *p* therein transversely to the fence-line, of the foot-piece C, having the slot *p'*, and the oblong socket-holes 15 *k*, for allowing the adjustment of the picket therein, as set forth.

7. The combination, with the base D, having the oblong vertical slot *p*, and the arm *j*, having the vertical hole *i*, with inclined sides,

of the brace *h* and the set-screw *i'*, with their 20 auxiliary connecting devices, as set forth.

8. In a punched fence having a picket adapted to engage with the rail, after being inserted, by a partial rotation on its axis, the combination, with said picket and rail, of an 25 ornament having its frame-bars bent over the front of the rail, the ends of said ornament inclosing said picket above and below said rail, and having sprockets extending from its frame-bars upon either side of the angle of the 30 picket, whereby the latter is prevented from turning, as set forth.

In testimony whereof I affix my signature in presence of two witnesses.

TIMOTHY ROGERS.
